MATERIAL STACKER

Stanley M. Mercier, Bexley, Ohio, assignor to The Jeffrey Manufacturing Company, a corporation of Ohio

Application February 3, 1949, Serial No. 74,348

22 Claims. (Cl. 198—118)

1

This invention relates particularly to a stacker for stacking or dumping material, such as sand, gravel and dirt which has been conveyed to a desired position by one or more belt conveyors.

An object of the invention is to provide improved interconnecting control means between a boom and a traction device, such as a crawler tractor, which is adapted to swing the boom in a generally horizontal plane through a substantial arc, whereby the discharge position of the material may be adjusted.

A further and more specific object of the invention is to provide means for interconnecting a stacker frame with the mast, post or pedestal of a tractor which includes a carriage providing for limited rectilinear movement between said post and said boom and switch means controlled thereby.

A further object is to provide mechanism as above described in which there is ball and socket means providing for limited tilting movement of the mast or post of the tractor relative to the boom.

Another object of the invention is to provide switch means operable whenever a desired limited travel has taken place between the carriage and the boom.

A further object of the invention is to provide switch means operable whenever the boom has tilted a predetermined amount.

Other objects of the invention will appear hereinafter, the novel features and combinations being set forth in the appended claims.

In the accompanying drawings,

Fig. 1 is a side elevational view of a stacker including the features of my invention and showing the generally horizontal boom together with the tractor for swinging it;

Fig. 2 is an elevational sectional view, different parts being taken along different sectional planes, showing particularly the connection between the upper end of the tractor mast, post or pedestal and the stacker boom;

Fig. 3 is a side elevational view, with parts in section, showing the structure of Fig. 2 of the drawings and being taken on the line 3—3 of Fig. 2;

Fig. 4 is a sectional view showing a modified double switch which may be substituted for the single tilt switch of Fig. 2;

Fig. 5 is a view, generally similar to Fig. 2, of a modified form of universal connection between the post and carriage of the stacker, together with a modified form of switch and actuating mechanism therefor;

Fig. 6 is a view in section, the section being taken on line 6—6 of Fig. 5;

Fig. 7 is a view in section of the structure seen in Fig. 5, the section being taken substantially on line 7—7 of Fig. 6; and

Fig. 8 is an enlarged view in plan showing a portion of the switch actuating mechanism shown in Fig. 5.

As seen in Fig. 1 of the drawings, the stacker includes a very long and large generally horizontal boom 10 which is fabricated from elongated structural members and reinforcing vertical and diagonal members. The boom 10 carries an endless belt conveyor 11 which is adapted to convey material from a feed hopper 12 and discharge it over the head pulley 13 of the conveyor. Such a boom is adapted particularly to convey granular material, such as rock, stone, dirt, gravel, sand, coal, or any similar material which it is desired to be conveyed and discharged. One illustration of the use of such a stacker is in connection with the removal and disposal of the overburden in a strip coal mining operation or in a strip iron ore mining operation. Other illustrations are the removal of material preparatory to the construction of dams and causeways.

The feed end of the boom 10 is mounted for swinging movement about both upright and horizontal axes on a car 14. The mechanism by which material is delivered to the hopper 12 is not illustrated as it forms no part of the invention here claimed. It may constitute a series of belt conveyors or a power shovel or the like.

Since the feed end of the boom 10 is preferably anchored in a fixed position for any swinging operation thereof, as for example, while it is swung very slowly through 180°, it is desirable to interconnect the tractor that supports and swings the boom and the boom so as to provide for limited longitudinal and rectilinear movement between the tractor and the boom and also to provide a relatively tilting movement between the two, since the ground or surface over which the tractor travels may be somewhat uneven.

The tractor for swinging the boom is seen at 15 and is illustrated as of the crawler type. It may be controlled by an operator in the operator's house 16 located on top of the boom 10 generally above the tractor 15.

To interconnect the tractor 15 with the boom 10 and provide the characteristics above mentioned, said tractor 15 has an elongated upwardly extending boom supporting mast, post or pedestal 17, to the upper end of which is rigidly attached a horizontal plate 18 (see Fig. 2), to which in turn there is rigidly attached a concave cup or socket 19 of what constitutes in effect a large ball and socket joint or bearing, the ball 20 of which is actually only a segment of a sphere having a lower convex or segmental spherical bearing surface which cooperates with the concave segmental spherical bearing surface of the socket 19, there preferably being a hard babbitt bearing liner 21 interposed between the ball 20 and socket 19 and preferably attached to the latter as by sweating or the like.

The ball and socket connection 19, 20 is one form of universal connection and preferably the one employed in this form of my invention. Obviously in certain broader aspects of my invention other universal type connections may be employed, such as a standard universal joint or the gimbal type universal connection.

Rigidly attached to and supported by the segmental ball 20 is a carriage 22 which includes a bed plate frame member 23 which is directly connected to the upper portion of said segmental ball 20. Laterally spaced and longitudinally extending upright plates 24 are connected to the bed plate 23, said plates 24 in turn carrying laterally extending spaced axles 25 to which there is a roller 26 attached on each end, being mounted thereon on anti-friction bearings 27. The four rollers 26 of the carriage 22 project between opposite upper and lower flanges of a pair of laterally spaced I-beams, rails or supporting tracks 28 which form an integral part of the boom 10. The inner upper and lower flanges of the I-beams, rails or supporting tracks 28 are provided with removable wear strips or tracks 29 which hold the boom 10 against any appreciable vertical or up and down movement with respect to the carriage 22. As clearly illustrated in Fig. 2 of the drawings, it is, of course, evident that the weight of the boom 10 is normally transmitted to the carriage 22 through the rollers 26 and upper tracks 29, the rollers 26 normally being out of engagement with the lower tracks 29. The carriage 22 also has four rollers 26 which cooperate with tracks 29 to take lateral thrust.

From the above description it is, of course, evident that the carriage 22 can move rectilinearly or longitudinally relative to the boom 10. It is desirable that this movement be restricted and in one illustration it is limited roughly to a travel of five feet so that the tractor 15 will not get too far away from its desired position of support for the boom 10. To this end there is preferably a pair of limit switches 30 (see Figs. 1 and 3), one located near each end of the desired travel of the carriage 22, the limit switches having operating handles or levers 31 adapted to be engaged by cams 32 carried on opposite ends of the carriage 22. The switches 30 may be employed to sound an alarm or to open the ignition circuit of the tractor 15.

The universal ball and socket joint 19, 20, 21 is preferably lubricated and to this end a lubrication feed pipe 33 connected to a source of lubri-

cating fluid under pressure extends through a horizontal bore in the plate 18 to a position adjacent the center thereof from which it extends upwardly to a cavity at the center of the cup or socket 19. Communicating with said cavity is a chamber 34 formed in the center bottom portion of the ball 20 to which a pressure gauge 35 is connected by a pipe or conduit 36.

Hydraulic fluid under pressure in the chamber 34 will find its way along the bearing liner 21 and any excess hydraulic fluid flowing over the peripheral edge of said liner will be received in a circumferential groove 37 formed in the socket 19. Groove 37 is connected to a drain pipe or conduit 38 and preferably has an oil level gauge 39 therein.

As clearly illustrated in Fig. 2 of the drawings the opposed segmental spherical surfaces of the joint 19, 20 extend beyond the circumferential groove 37 but beyond said groove there is no interposed bearing liner 21. At the periphery of the socket 19 there is a wiper 40 made of leather, rubber or the like, which is rigidly attached to the socket 19 by a metal band or the like and which has wiping engagement with the ball 20 around a small circle thereof, thus preventing any substantial leakage of lubricating material beyond this point.

In view of the above described universal connection between the carriage 22 and the mast, post or pedestal 17 it is obvious that said carriage 22 and the boom 10 which it supports is free to tilt in any direction or universally relative to said post 17. It is evident, however, that this tilting movement should not be allowed to progress to an unreasonable extent as this might upset the tractor 15 and damage the equipment and possibly injure the operator.

The freedom of relative tilting movement, however, is desirable because of the unevenness or irregular undulations of the ground or bed over which the tractor 15 must ride. In this regard it may be stated that the universal connection provides a third point of an essential three-point support for the boom 10, it being mounted at its rear for swinging movement on a horizontal axis which is designed to prevent any appreciable lateral tilting of said boom 10.

In order to give a signal or effect a control whenever the post 17 is tilted a limited safe amount relative to the boom 10, a limit switch is provided which is closed whenever said limit is reached. Said switch comprises a pair of rings 41 and 42 of conducting material which are carried in a sheathing flexible ring or continuous tube 43 of rubber or the like. The rings 41 and 42 are normally spaced apart, as illustrated in Figs. 2 and 3 of the drawings, as is provided by the dimension of the enclosing ring or casing 43. The upper ring 41 is supported by a plurality of spaced chain hangers 44 preferably provided with insulating blocks 45, thereby to insulate the ring 41 from its supporting structure. Chains 44 are in turn supported from the bed plate 23 by brackets 46.

As is evident from Figs. 2 and 3 of the drawings, the switch structure 41, 42, 43 is thereby normally suspended from the bed plate 23 in a position surrounding the top plate 18 of the post or pedestal 17.

Tilting movement of the post 17 relative to carriage 22 in any direction will produce a lowering of some portion of the ring 41, 42, 43 and when said post or pedestal is tilted a predetermined amount in any direction the lower

edge of the ring switch 41, 42, 43 will contact a circumferential angle member 47 which is mounted on the bottom of the plate 18. This contacting of the switch 41, 42, 43 with the angle 47 will support the ring 42 and bring it into contact with the ring 41. Rings 41 and 42 therefore comprise the two contacts of a switch, which switch is employed to give an alarm or to control desired mechanism as above suggested.

In the operation of the device, material to be conveyed and discharged or stacked is delivered to the feed hopper 12 and conveyed by the belt conveyor mechanism 11 to discharge over the head pulley 13. Continuously or intermittently during this discharging operation the boom 10 will be swung about an upright axis through any desired arc, such as 180°, by the travel of the tractor 15.

One type of operation involves the successive swinging of the boom or stacker, followed by forward feeding of the position of the feed hopper 12, thereby to produce a spoilage pile over which the stacker progresses. As the tractor 15 travels over any uneven surface to swing the boom 10 the limited freedom of rectilinear or longitudinal freedom of rectilinear or longitudinal movement between the carriage 22 and the boom 10 relieves the pivotal attachment for the rear end of the boom 10 of strains, particularly rectilinear strains along the longitudinal axis of said boom which would occur if the tractor 15 were rigidly attached to the boom 10.

The switch means 30, however, prevent undue relative travel between the post 17 of tractor 15 and the boom 10, thus insuring that support for the boom 10 is maintained reasonably at the proper position.

As the tractor 15 moves over uneven ground, strain is not transmitted to the boom because the post 17 is free to follow the tendency of the tractor to accommodate itself to the uneven or irregularly undulated ground due to the ball and socket connection 19 and 20 which is the preferred form of universal connection between the carriage 22 and the mast, post or pedestal 17, since this universal connection provides for limited relative tilting between the boom 10 and said post or pedestal 17.

To prevent damage which might occur in an extreme case of relative tilting, the switch 41, 42, 43 is provided to give an alarm or effect any desired control whenever the limit of safe tilting has been reached. It is thus evident that mechanism has been provided which will relieve considerable of the strain otherwise inherent in a tractor swung boom which is adapted to travel over uneven or irregularly undulated ground.

In Fig. 4 of the drawings a modified form of switch is illustrated which may be substituted for the switch 41-43. The principal feature of this modified switch is that it is a double or duplex switch and it operates so that on a predetermined tilt one pair of contacts will be closed, which may, for example, give an alarm, whereas if a greater tilt is realized or effectuated a second pair of contacts may be actuated which, for example, may disable the driving motor for the crawlers.

Said switch of Fig. 4 includes a ring-like enclosing sheathing or endless tube 48 of rubber or the like, in which there are three enclosed concentric rings 49, 50 and 51, all made of conducting material. Ring 49 is supported in the same manner that ring 41 of Fig. 2 is supported. Ring 51 is likewise supported as was ring 42 of

Fig. 2. Ring 50 is interposed between rings 49 and 51 and is rigidly attached at substantially the center of the enclosing sheathing 48, thus being normally held out of contact with both rings 49 and 50. Obviously, upon a predetermined tilting of the post 17 relative to the boom 10 or carriage 22, ring 51 will first be brought into contact with ring 50, closing or actuating the switch provided by these two rings. Further tilting will lift the two rings 50 and 51 together and cause ring 50 to contact ring 49, thus actuating the second switch provided by said rings 49 and 50, which may shut down the apparatus.

In Figs. 5, 6, 7 and 8 of the drawings there is illustrated a modified form of universal support for the boom 10, as well as a different type of switch and actuating means therefor which may be substituted for the corresponding parts shown in Figs. 1 through 3. In said Figs. 5, 6, 7 and 8 there is an upstanding elongated mast, post or pedestal 52 which is essentially the same as the mast, post or pedestal 17 and has the same relation with a tractor 15.

The boom 10 is provided with I-beams 53 which are essentially similar to the above described I-beams 28 and are provided with top wear tracks 54 and bottom wear tracks 55. A carriage 56 is universally supported on top of the mast 52 by right angle trunnions in a generally horizontal plane, one of which trunnions is provided by a shaft 57 journaled at opposite ends to cross axles or frame members 58 of said carriage 56, which axles 58 carry boom supporting rollers 59 on opposite ends thereof, which rollers 59 support the I-beams 53 through the wear tracks 54.

Lateral thrust is transferred from the carriage 56 to the I-beams 53 by four laterally spaced bearing wheels 60 carried on the bottom of the carriage 56. The shaft 57 is mounted on a pin 81 carried by spaced trunnions 82, the axis of which pin is at right angles to the axis of the shaft 57, said trunnions 82 and pin 81 being carried on a swivel plate 83 in the top housing 61 of the mast 52.

Rigidly attached to and depending downwardly from the carriage 56 are four spaced arms 62 which at their bottoms are adjustably attached to a circumscribing angle shaped ring 63, which circumscribes the upper end of the mast or pedestal 52. It is evident that the ring 63 will partake of the movement of the carriage 56 and as the mast or pedestal 52 tilts relative to the boom 10 and carriage 56, the position of the ring 63 will vary with respect to said post or pedestal 52.

Near the top of the post or pedestal 52 and below the housing 61 there is a pivot ring 64 which is rigidly attached to the said post or pedestal 52 by a plurality of peripherally spaced brackets 65. The ring 64 pivotally supports a plurality of bell crank levers 66, of which there are a large number, being appropriately journaled on said ring 64, as clearly illustrated in Fig. 6 of the drawings. The levers 66 have downwardly extending arms which together form a skirt, something like a grass skirt, surrounding the mast or post 52. Said downwardly extending arms normally contact the inner edge of the actuating ring 63.

The levers 66 also have inwardly and preferably downwardly sloping arms which normally rest upon a stop ring 67 carried by the brackets 65. Normally resting on the inwardly extending arms of the levers 66 is an actuating ring 68 which surrounds the post 52. Diametrically ex-

tending right angle cross rods 69 extend between opposite sides of the ring 68 and through slots in the post 52.

At the center of the ring 68, which is normally at the center of the post 52, there is a block 70 to which said rods 69 are attached. The block 70 is provided with a downwardly extending hook 71 which is hooked to a substantially vertically hanging actuating rod 72 which at its bottom is pivotally attached to a pivoted cross lever 73, which cross lever 73 is pivotally attached at one end to a bracekt on the post or pedestal 52 and at the other end carries a pair of cam operated switches 74 and 75, there being one adjacent each side thereof. The switches 74 and 75 are provided with individual operating arms or levers 76 and 77, respectively, adapted to be operated in sequence by cams 78 and 79, respectively, and carried on the inside of a housing 80 attached to the pedestal 52.

The operation of the tilt control means of Figs. 5 and 6 is as follows. With substantially no tilt between the pedestal or post 52 and the carriage 56 or boom 10, the switch operating parts will be in the position illustrated in Fig. 5 of the drawings. Whenever tilting action takes place between the post 52 and the carriage 56 or boom 10, the operating ring 63 will press down on the outwardly and downwardly extending arms of one or more of the bell crank levers 66. This action will, of course, tend to raise the ring 68 by the actuating levers, pivoting it on the diametrically opposite side where it will rest on the inwardly extending arms of the opposite bell crank levers 66.

This pivotal movement of the ring 68 will be transferred by rods 69 to pull upwardly on the rod 72 and swing the switch lever 73 upwardly about its pivot. This upward swinging will elevate the two switches 74 and 75 so that upon a predetermined tilting movement, one of said switches 74, 75 will be actuated by virtue of its lever or arm 76 or 77 engaging a cam 78 or 79. Further tilting movement will be required to operate the other switch 74 or 75, thus providing the initial signal or alarm condition previously described, followed by the final warning or alarm or the actual shutting down of the apparatus.

It is evident that the lever 73 and thus the two control switches 74 and 75 will be operated on a predetermined tilt between the mast or pedestal 52 and the boom 10 or carriage 56, regardless of the particular direction in which this tilt takes place, since the skirt like bell cranks 66 completely surround the mast or pedestal 52. Obviously, within certain broad aspects of the invention, one of the switches 74, 75 may be omitted.

Obviously those skilled in the art may make various changes in the details and arrangement of parts without departing from the spirit and scope of the invention as defined by the claims hereto appended, and applicant therefore wishes not to be restricted to the precise construction herein disclosed.

Having thus described and shown an embodiment of the invention, what it is desired to secure by Letters Patent of the United States is:

1. A stacker including an elongated boom having conveyor mechanism thereon adapted to convey and discharge material, traction means operable to travel directly upon and over irregularly undulated ground and swing said boom in a generally horizontal movement, said traction means including an elongated upstanding boom

supporting mast, means interconnecting the boom to the upper end of said mast providing free tilting movement between them and also providing for rectilinear movement of said mast relative to said boom, said interconnecting means including a trackway extending longitudinally along said boom, a carriage having wheels rolling on said trackway, means cooperating with said trackway to maintain said carriage and boom in a relatively fixed horizontal position while providing for rectilinear movement of said carriage relative to said boom, mechanism providing a substantially universal connection between said carriage and the top of said mast, said universal connection mechanism including cooperating concave-convex surface forming bearing means, switch means operable whenever said carriage reaches a predetermined position on said boom, and switch means operable on a predetermined tilting of said mast.

2. A stacker including an elongated boom having conveyor mechanism thereon adapted to convey and discharge material, traction means operable to travel over the ground and swing said boom in a generally horizontal movement, said traction means including an upstanding boom supporting mast, means interconnecting the boom to the upper end of said mast, said means including a carriage, means supporting said boom from said carriage while providing for limited rectilinear movement between them, means interconnecting said carriage and said mast for relative tilting movement, and switch means including a suspended flexible tube and a pair of ring contactors therein operable on a predetermined tilting of said mast relative to said carriage.

3. A stacker including an elongated boom having conveyor mechanism thereon adapted to convey and discharge material, traction means operable to travel directly upon and over irregularly undulated ground and swing said boom in a generally horizontal movement, said traction means including an elongated upstanding boom supporting mast, means interconnecting the boom to the upper end of said mast, said means including a carriage, means supporting said boom from said carriage while providing for limited rectilinear movement between them, switch means operable whenever said carriage reaches a predetermined position relative to said boom, and means interconnecting said carriage and said mast.

4. A stacker including an elongated boom having conveyor mechanism thereon adapted to convey and discharge material, traction means operable to travel over the ground and swing said boom in a generally horizontal movement, said traction means including an upstanding boom supporting mast, means interconnecting the boom to the upper end of said mast including a universally tiltable mechanism, and dual switch means operable to close one pair of contacts on a predetermined tilting of said mast and to close a second pair of contacts on a greater tilting thereof, said switch means including three concentric conducting rings normally held in spaced relation and sheathed in a supporting tube of insulating material.

5. A stacker including an elongated boom having conveyor mechanism thereon adapted to convey and discharge material, traction means operable to travel over the ground and swing said boom in a generally horizontal movement, said traction means including an upstanding

boom supporting mast, means interconnecting the boom to the upper end of said mast including a universally tiltable mechanism, and dual switch means operated automatically in response to a predetermined movement of said universally tiltable mechanism to operate one pair of contacts and upon further movement of said universally tiltable mechanism to operate a second pair of contacts.

6. A stacker including an elongated boom having conveyor mechanism thereon adapted to convey and discharge material, traction means operable to travel directly upon and over irregularly undulated ground and swing said boom in a generally horizontal movement, said traction means including an elongated upstanding boom supporting mast, means interconnecting the boom to the upper end of said mast including a universally tiltable mechanism, and switch means operated automatically in response to a predetermined tilting of said mast with respect to said boom to operate a pair of contacts.

7. A stacker including an elongated boom having conveyor mechanism thereon adapted to convey and discharge material, traction means operable to travel over the ground and swing said boom in a generally horizontal movement, said traction means including an upstanding boom supporting mast, means interconnecting the boom to the upper end of said mast including a universally tiltable mechanism, switch means operable upon a predetermined tilting of said mast, actuating mechanism for said means including a normally horizontal ring carried by said boom, a plurality of pivoted bell crank levers carried by said mast and having arms extending downwardly skirt like around said mast and surrounded by said ring, and means operating said switch means when any of said bell crank levers is pivoted a predetermined amount.

8. A stacker including an elongated boom having conveyor mechanism thereon adapted to convey and discharge material, traction means operable to travel over the ground and swing said boom in a generally horizontal movement, said traction means including an upstanding boom supporting mast, means interconnecting the boom to the upper end of said mast including a universally tiltable mechanism, switch means operable upon a predetermined tilting of said mast, actuating mechanism for said means including a normally horizontal ring carried by said boom, a plurality of pivoted bell crank levers carried by said mast and having arms extending downwardly skirt like around said mast and surrounded by said ring, means operating said switch means when any of said bell crank levers is pivoted a predetermined amount, and a second switch means operable by further tilting of said mast.

9. A stacker including an elongated boom having conveyor mechanism thereon adapted to convey and discharge material, means mounting one end of said boom for movement about an upright and a horizontal axis, traction means operable to travel over an uneven surface and swing said boom laterally while supporting it, said traction means including an upstanding boom supporting mast, means interconnecting the boom to the upper end of said mast including a carriage movable rectilinearly with respect to said boom through a limited travel and universally tiltable mechanism, switch means adapted to be actuated by said carriage when either limit of travel of said carriage is reached, switch

means and mechanism for operating it upon a predetermined tilting of said mast including ring means, means carrying said ring means whereby the latter follows the movement of said carriage and surrounds said mast, and means on said mast adapted to engage said ring means when said mast is tilted said predetermined amount.

10. A stacker including an elongated boom having conveyor mechanism thereon adapted to convey and discharge material, means mounting one end of said boom for movement about an upright and a horizontal axis, traction means operable to travel over an uneven surface and swing said boom laterally while supporting it, said traction means including an upstanding boom supporting mast, means interconnecting the boom to the upper end of said mast including a carriage movable rectilinearly with respect to said boom and universally tiltable mechanism, switch means and mechanism for operating it upon a predetermined tilting of said mast including ring means, means carrying said ring means whereby the latter follows the movement of said carriage and surrounds said mast, and means on said mast adapted to engage said ring means when said mast is tilted said predetermined amount.

11. A stacker including an elongated boom having conveyor mechanism thereon adapted to convey and discharge material, means mounting one end of said boom for movement about an upright and a horizontal axis, traction means operable to travel over an uneven surface and swing said boom laterally while supporting it, said traction means including an upstanding boom supporting mast, means interconnecting the boom to the upper end of said mast including a universally tiltable mechanism, switch means and mechanism for operating it upon a predetermined tilting of said mast including ring means, means carrying said ring means whereby the latter follows the movement of said universally tiltable mechanism and surrounds said mast, and means on said mast adapted to engage said ring means when said mast is tilted said predetermined amount.

12. A stacker including an elongated boom having conveyor mechanism thereon adapted to convey and discharge material, means mounting one end of said boom for movement about an upright and a horizontal axis, traction means operable to travel over an uneven surface and swing said boom laterally while supporting it, said traction means including an upstanding boom supporting mast, means interconnecting the boom to the upper end of said mast including a carriage movable rectilinearly with respect to said boom through a limited travel and universally tiltable mechanism, switch means adapted to be actuated by said carriage when either limit of travel of said carriage is reached, switch means and mechanism for operating it upon a predetermined tilting of said mast including means carried to follow the movement of said carriage, and means adapted to engage said last named means when said mast is tilted said predetermined amount.

13. A stacker including an elongated boom having conveyor mechanism thereon adapted to convey and discharge material, means mounting one end of said boom for movement about an upright and a horizontal axis, traction means operable to travel over an uneven surface and swing said boom laterally while supporting it,

said traction means including an upstanding boom supporting mast, means interconnecting the boom to the upper end of said mast including a carriage movable rectilinearly with respect to said boom and universally tilttable mechanism, switch means and mechanism for operating it upon a predetermined tilting of said mast including means carried to follow the movement of said carriage, and means adapted to engage said last named means when said mast is tilted said predetermined amount.

14. A stacker including an elongated boom having conveyor mechanism thereon adapted to convey and discharge material, means mounting one end of said boom for movement about an upright and a horizontal axis, traction means operable to travel over an uneven surface and swing said boom laterally while supporting it, said traction means including an upstanding boom supporting mast, means interconnecting the boom to the upper end of said mast including a universally tilttable mechanism, switch means and mechanism for operating it upon a predetermined tilting of said mast including means carried to follow the movement of said universally tilttable mechanism, and means adapted to engage said last named means when said mast is tilted said predetermined amount.

15. A stacker including an elongated boom having conveyor mechanism thereon adapted to convey and discharge material, means mounting one end of said boom for movement about an upright and a horizontal axis, traction means operable to travel over an uneven surface and swing said boom laterally while supporting it, said traction means including an upstanding boom supporting mast, means interconnecting the boom to the upper end of said mast including a carriage movable rectilinearly with respect to said boom through a limited travel and universally tilttable mechanism, and switch means adapted to be actuated by said carriage when either limit of travel of said carriage is reached.

16. A stacker including an elongated boom having spaced longitudinally extending rails and conveyor mechanism thereon, means mounting one end of said boom for movement about an upright and a horizontal axis, boom supporting means operable to travel and swing laterally with said boom including an upstanding boom supporting mast, means interconnecting the boom to the upper end of said mast including a carriage movable rectilinearly between said rails through a limited travel and universally tilttable mechanism, switch means adapted to be actuated when either limit of travel of said carriage is reached, a switch and mechanism for operating it upon a predetermined tilting of said mast including means carried by said carriage, and means adapted to engage said last named means when said mast is tilted said predetermined amount.

17. A stacker including an elongated boom having spaced longitudinally extending rails and conveyor mechanism thereon, means mounting one end of said boom for movement about an upright and a horizontal axis, boom supporting means operable to travel and swing laterally with said boom including an upstanding boom supporting mast, means interconnecting the boom to the upper end of said mast including a carriage movable rectilinearly between said rails through a limited travel and universally tilttable mechanism, a switch and mechanism for operating it upon a predetermined tilting of said mast including means carried by said carriage, and means adapt-

ed to engage said last named means when said mast is tilted said predetermined amount.

18. A stacker including an elongated boom having spaced longitudinally extending rails and conveyor mechanism thereon, means mounting one end of said boom for movement about an upright and a horizontal axis, boom supporting means operable to travel and swing laterally with said boom including an upstanding boom supporting mast, means interconnecting the boom to the upper end of said mast including a carriage movable rectilinearly between said rails through a limited travel and universally tilttable mechanism, and switch means adapted to be actuated when either limit of travel of said carriage is reached.

19. Mechanism for supporting a stacker boom including a support, means above said support adapted to be connected to said boom, means interconnecting said support and the means thereabove providing free tilting movement between them, said interconnecting means including mechanism providing a substantially universal connection between said support and the means thereabove, a switch and mechanism for operating it upon a predetermined tilting of said support with respect to said boom including a hollow flexible ring surrounding said support, at least two spaced ring contact means within said hollow flexible ring one above the other, means supporting said hollow flexible ring to follow the movement of said means above said support, and means associated with said support for moving said contact rings into engagement when said support is tilted said predetermined amount.

20. Mechanism for supporting a stacker boom including a support, means above said support adapted to be connected to said boom, means interconnecting said support and the means thereabove providing free tilting movement between them, said interconnecting means including mechanism providing a substantially universal connection between said support and the means thereabove, a switch and mechanism for operating it upon a predetermined tilting of said support with respect to said boom including mechanism supported to follow the movement of said means above said support, and mechanism associated with said support for engaging said supported mechanism when said support is tilted said predetermined amount.

21. Mechanism for supporting a stacker boom including a support, means above said support adapted to be connected to said boom, means interconnecting said support and the means thereabove providing free tilting movement between them, said interconnecting means including mechanism providing a substantially universal connection between said support and the means thereabove, a switch and mechanism for operating it upon a predetermined tilting of said support with respect to said boom including a ring surrounding said support, and bell crank means associated with said support adapted to be moved when said support is tilted said predetermined amount to operate said switch.

22. Mechanism for supporting a stacker boom including a pair of spaced track members adapted to carry the boom to be supported, a carriage, means on said carriage engaging said spaced track members whereby said carriage may move between said spaced track members, a support below said carriage, and mechanism interconnecting said carriage and support providing a substantially universal connection between them, said interconnecting means including cooperat-

13

ing concave-convex surface forming bearing means.
